UNITED STATES PATENT OFFICE.

GEORGE HENRY, OF SAN FRANCISCO, CALIFORNIA.

CHECK AND MONEY-ORDER CASE.

1,420,260.

Specification of Letters Patent. Patented June 20, 1922.

Application filed August 13, 1919. Serial No. 317,181.

To all whom it may concern:

Be it known that GEORGE HENRY, a citizen of the United States, residing at the city and county of San Francisco and State of California, has invented new and useful Improvements in Check and Money-Order Cases, of which the following is a specification.

This invention relates to a case and particularly pertains to a structure adapted to hold checks or money orders.

It has been a problem among banking and commercial houses to provide some means for safely guarding checks and like papers and especially to prevent checks or money orders from being torn from the center of a book and thus not detected until some time after the theft. It is the principal object of the present invention to provide a container adapted to receive a continuous roll of checks or money orders and thus insuring that but the outermost of the checks can be removed at a time and at the same time providing a very convenient means for locking the unused checks so that there will be slight danger of theft of the roll or of any checks upon the roll.

The present invention contemplates the use of a cylindrical container having one side movable so that a roll of checks may be exposed; the container being provided with means whereby a roll of checks may be held in a rotatable position therein and may be easily inserted or removed therefrom and furthermore, the container is fitted with simple means whereby the movable door may be locked in position to prevent access to the checks contained therein.

The invention is illustrated by way of example in the accompanying drawings, in which—

Fig. 1 is a view in front elevation, showing the complete container and indicating by dotted lines the outermost positions of the center supporting pin.

Fig. 2 is a view in end elevation showing the complete container with a portion of its base broken away to illustrate the locking member.

Fig. 3 is a view in vertical section through the container as seen on the line 3—3 of Fig. 1 and clearly shows the position of the roll of checks within the container and the manner in which they may be successively withdrawn therefrom.

Fig. 4 is an enlarged fragmentary view of the center pin carried at one end of the container.

Fig. 5 is a fragmentary view showing the yieldable construction of the pin shown in Fig. 4.

Fig. 6 is an enlarged fragmentary view showing the center pin construction utilized at the opposite end of the container.

Fig. 7 is a view in end elevation showing the formation of the end of the check roll axle.

Fig. 8 is a fragmentary view showing the manner in which the movable side of the container is held by the container end.

Fig. 9 is a view in diagram illustrating one of the checks forming the roll.

Referring more particularly to the drawings, 10 indicates a rectangular base member which may be securely fastened to a permanent support and upon which a sheet metal base housing 11 is mounted. This housing has parallel opposite ends and tapering front and back faces 12 and 13. At certain points around the space are tangs 14 which are inturned and receive screws 15, by which the base portion 11 may be fastened upon the portion 10 and the screws held in a concealed position. As shown in Fig. 3, the front and rear faces 12 and 13 terminate at opposite sides of a horizontally extending arcuate portion 16. This portion is described from the center of the container 17 and forms a continuation of the container wall. The rear of this container has a fixed wall portion 18 substantially describing a semi-circle and being supplemented by the front moving wall portion which is clearly shown in Fig. 3. The fixed wall portion 18 and the movable wall portion 19 are held between end members 20 and 21 which are secured to the opposite ends of the metal base portions 11. The sliding connection for the forward movable wall portion 19 is clearly shown in Fig. 8, where it will be seen that the ends are formed with outer plates 22 and inner plates 23. These plates have annular flanges 24 and 25 spaced from each other to receive the ends of the member 19 and to permit it to slide therearound.

The member 19 may be moved to the position indicated by dotted lines in Fig. 3, and when so disposed will completely expose a roll 26 of checks as indicated at 27.

The roll of checks is mounted upon a cen-

tral axle 28, one end of which is formed with a transverse slot 29 to receive pins 30. These pins are formed upon a circular plate 31 adapted to rest against the square end of the 5 axle 28 and to form a support therefor, as well as to provide means whereby the axle may be rotated. The disc 31 has a trunnion member 32 extending from it and projecting into a central opening 33 of the axle. 10 The opposite side of the disc is formed with an enlarged portion 34 which is reduced in diameter at its outer end to provide a pin 35 upon which a knob 36 is fixed. The hump portion of this knob normally rests against 15 a protrusion formed in the end plate 22 and is held in this position by means of an expansion spring 37 acting against a sleeve 38 at one end and the shoulder of the portion 34 at its opposite end. It will thus be seen 20 that by drawing outwardly on the knob, the pins 30 and the disc 31 may be drawn away from the end of the axle and will partially permit its removal. The complete disengagement of the axle is produced by means 25 of a pin member 40 carried in the opposite end 20 of the case. This pin member is formed with a thumb piece 41, by which it may be drawn into the yieldable sleeve 42 and will be held within this sleeve until 30 forced inwardly to seat within the end of the bore 33.

In order that the container may be locked when desired, the movable member 19 is formed with an out-turned flange portion 35 44 along its lower marginal edge. The angle of this flange is such as to cause it to lie flat upon the front face 13 of the metal base member. A slotted opening 45 is formed to this member and is adapted to 40 receive a lock lug 46 carried upon a lock lever 47. This lug extends through a similar opening 48 in the plate 13 and projects outwardly sufficient so that a lock bolt opening 49 will be exposed through the flange and 45 will receive the bolt of padlock 50, as shown in Fig. 2. The movement of the lug 46 is brought about by the member 47 which is carried upon a concealed pin 51 and which may be elevated to its locking position by 50 suppressing the outer extending portion of the lever.

Reference being had to Fig. 9, it will be seen that the checks are preferably formed with stub portions A and body portions B. 55 The stub portions and body portions are separated by a perforation and the two members which combine to form one complete check are separated from the succeeding checks by transverse perforation. After the 60 check has been withdrawn and the stub separated therefrom, it is desirable to place the stub in a convenient position, relative to the container. For this purpose a vertically extending compartment 52 is fixed upon the 65 back of the metal base and extends upwardly

with an open mouth into which the stubs may be placed as the checks are used, and after use may be filed away.

In operation of the present invention the knobs 36 and 41 are first drawn outwardly 70 to provide clearance for axle 28. This axle is then inserted as indicated in Figures 4 and 6, respectively, after which the spring members of the pins 40 and 32 may be released to properly support the axle and to 75 provide simple means for its rotation, during this operation it will be understood that the movable member 19 is in its uppermost position, as indicated by dotted lines in Fig. 3 and that after the foremost check has been 80 drawn from the container, this member may be moved down to the solid line position, shown in the same figure. When in this position the checks may be successively withdrawn and filled out. The separate checks 85 being torn from the roll and their stubs thereafter separated and placed in the compartment 52. It will thus be evident that there will be no possibility for underlying checks in the roll to be extracted but that by 90 maintaining a close watch upon the members of the checks, the removal of any one check would be immediately detected.

When it is desired to lock the container the thumb knob 36 may be rotated to draw 95 the checks in and wind them upon the roll, after which the lever 47 may be suppressed at its outer end to swing the lugs 46 upwardly through perforations 45 and 48. Any suitable lock may then be caused to engage the lugs 46 and prevent the upward swinging of the wall member 19. 100

It will thus be seen that by providing a container, as here shown and securing it to a permanent fixture, it will be impossible for 105 an unauthorized person to remove checks from the container without completely mutilating the device and furthermore, it will be seen that a very simple and desirable device will be provided for receiving checks 110 and from which checks and other instruments of like character may be easily withdrawn.

While I have shown the preferred form of my invention, as now known to me, it 115 will be understood that various changes in the combination, construction and arrangement of parts may be made by those skilled in the art, without departing from the spirit of the invention, as claimed. 120

Having thus described my invention, what I claim and desire to secure by Letters Patent is:—

1. In a device of the character described, a hollow base having upwardly converging sides, a cylindrical container mounted upon the upper ends of said sides, said container having a fixed back wall, and a slideable front wall complementary thereto, end members secured to the fixed back wall, and within which 125 130

the opposite end edges of the movable front wall may slide, a lip formed longitudinally of the lower side of the front wall adapted to be disposed in parallel relation to the corresponding side of the base when in its lowered position, said lip and side of base being provided with register slots, a locking pin concealed within the hollow base, means by which said pin may be raised to extend 10 through said slots, and a lock by which said pin may be held in its raised position.

2. In a device of the character described, a hollow base having upwardly converging sides, a cylindrical container mounted upon 15 the upper ends of said sides, said container having a fixed back wall, and a slidable front wall complementary thereto, end members secured to the fixed back wall, and within which the opposite end edges of the movable 20 front wall may slide, and a lip formed longitudinally of the lower side of the front wall adapted to be disposed in parallel relation to the corresponding side of the base when in its lowered position, said lip and 25 side of base being provided with register slots, a lever extending transversely of the base carrying on its inner end a locking pin and its outer end extending from the casing by which said pin may be swung upwardly by 30 which said pin may be swung upwardly through said slots, and means for locking said pin in the last named position.

3. A container comprising a hollow base

having upwardly convergent sides, a cylindrical container mounted on said base, said container having a fixed back wall, and a 35 slidable front wall complementary thereto, end members secured to the fixed back wall, guides formed on the end members within which the opposite end edges of the slidable front wall may slide, a lip formed longitudinally of the lower side of the front wall adapted to be disposed in parallel relation to the corresponding side of the base when in its lowered position, said lip and side of base 40 being provided with register slots, a lever extending transversely of the base carrying on its inner end a locking pin and its outer end extending from the casing by which said pin may be swung through said slots, means 45 for locking said pin in the last named position, a slidable trunnion carried by each end of the container and adapted to engage the axle of a roll of checks, said trunnions having spring controlled endwise movement and are adapted to support the axle and 50 frictionally retard rotation thereof.

In testimony whereof I have hereunto set my hand in the presence of two subscribing witnesses.

GEORGE HENRY.
